M. E. WINKS

FUSE PLUG

Filed Jan. 6, 1921

INVENTOR.
Miles E. Winks

BY

Z. Ledermann
ATTORNEY.

UNITED STATES PATENT OFFICE.

MILES EDWARD WINKS, OF SAN JOSE, CALIFORNIA, ASSIGNOR OF ONE-HALF TO
HOMER THOMAS WAGGONER, OF STROH, INDIANA.

FUSE PLUG.

Application filed January 6, 1921. Serial No. 435,375.

To all whom it may concern:

Be it known that I, MILES EDWARD WINKS, a citizen of the United States, residing at San Jose, in the county of Santa Clara and 5 State of California, have invented certain new and useful Improvements in Fuse Plugs, of which the following is a specification.

The main object of this invention is the provision of a fuse plug having means for 10 rapidly replacing the burnt fuse wire after a blowout, thereby possessing the quality of economy as well as that of adaptability to emergencies. By means of the new plug, a system which has been impaired by the blowing 15 of a fuse may be repaired in a very short time, by simply replacing the burnt wire with a new wire.

The above and other objects will become apparent in the description below, in which 20 like-named characters of reference refer to like-named parts in the drawings.

Referring briefly to the drawings, Fig. 1 is a central longitudinal cross-sectional view 25 of the plug.

Fig. 2 is a perspective view, partly in section, of the removable cap of my plug.

Fig. 3 is a cross-sectional view on the line 3—3 of Fig. 1.

Fig. 4 is a partial elevational view on the 30 line 4—4 of Fig. 1 with the cap removed.

Fig. 5 is a cross-sectional view on the line 5—5 of Fig. 1.

Referring in detail to the drawings, the 35 numeral 1 represents the body of the plug, which may be made of porcelain, as usual. In the base of said body a recess 2 is provided for the secure and tight reception 40 therein of a cap 3 having an upwardly extending rigid square tube 4. A post 5 of brass or the like is united to the screw shell 6 as shown, the post having rigid with the top thereof a spring or resilient clip 7. Resilient legs 8 are provided on the clip, between which the upper end of the fuse wire 9 45 may be clamped and securely retained. The lower end of the wire is soldered to the inside of the tube 4. In the sale of the plug, a number of caps 3 previously provided with fuse wires 9 already soldered in the tube 4 of each, are provided with each plug.

The upper portion of the body of the plug

is provided with a pair of diametrically opposed T shaped recesses extending a short distance radially into the plug body forming in effect the female elements of a bayonet lock comprising a central open portion 10, the under cut recesses 12 and the overhanging ledges 15. The fuse cap 13 is preferably made of brass, and is provided with resilient clips or ears 11 adapted to register with the recesses 12 to releasably retain the cap on the plug. In order to remove the cap, it is apparent that the latter need be turned until the ears 11 register with the recesses 10, when the cap is free to be drawn upward from the body of the plug. In attaching the cap, it is also apparent that the same must be applied with the ears sliding in the recesses 10, and the cap may then be turned in either direction until the ears engage the recesses 12, by which the cap is retained by the upper eaves 15.

Therefore, assuming that the plug has been used and that the fuse wire therein has been blown out, the plug is first unscrewed 75 from its socket as any ordinary plug. Then the cap 13 is removed as above described, and the upper end of the wire removed from the resilient clip 7. Then the cap 3 is withdrawn from the bottom of the plug, the 80 lower portion of the wire coming out with the cap 3. A new cap, with fuse wire already provided on its tube 4, is then inserted thru the recess 3, and the upper end is forced between the legs 8 of the clip 7. 85 Finally, the cap 13 is replaced, and the fuse is again ready for use.

In order to further insure the insulating quality of the plug, an insulating non-inflammable disc 16 is provided between the 90 cap 13 and the upper surface of the body 1, this disc also operating to prevent the entrance of moisture and also to prevent the fuse wire from uniting with the cap at the instant of fusion, when the fuse plug is used 95 in certain positions.

I claim:

A fuse plug comprising a hollow body composed of insulating material, a screw shell mounted on said body, a cap covering the top of said body, a terminal cap on the bottom of said body, a post within said body 100

united to the shell, said post having threads on its outer face corresponding to the threads on the screw shell, resilient parallel fingers having a vertical channel and extending at right angles from the free end of the post toward the interior of the body, the corners of said fingers mutually facing each other be-

ing rounded, a hollow stem, and a fusible link fixed in the hollow stem and adapted to be received between the resilient fingers to establish electrical connection between the shell and the terminal cap of the fuse. 10

In witness whereof I affix my signature.

MILES EDWARD WINKS.
